UNITED STATES PATENT OFFICE.

OSCAR J. MARTINSON, OF CHICAGO, ILLINOIS, ASSIGNOR TO MONIGHAN MACHINE CO., OF CHICAGO, ILLINOIS, A CORPORATION OF ILLINOIS.

TRACTION MACHINE.

Application filed April 24, 1925. Serial No. 25,587.

The purpose of this invention is to provide improvements in traction or propulsion mechanism for heavy machinery. The new construction is herein shown as applied to 5 an excavating machine and it is intended that this mechanism accomplish in a more perfect manner the work performed by the traction mechanism described in applicant's Patent No. 1,101,460, June 23, 1914, excavator tractors. The patented arrangement has met with considerable success in moving excavators, as required under average conditions where work is performed by such machines, such as the digging of drainage 10 ditches through sometimes rough and otherwise uneven ground including gradual slopes, sand, muddy or marshy land. It is at times necessary for such machines to work in places where water is two or three 15 feet deep and the bottom soft, and they are, therefore, provided with main and auxiliary supporting platforms of considerable area. The present construction is designed along somewhat similar lines in that the working 20 machine rests upon a large base around which the machine may turn on a circular track and vertical king-pin in order that the bucket carrying beam may extend in any desired direction from the machine. The 25 machine is provided with a heavy horizontal shaft, which supports, at its ends, large auxiliary bases through eccentrics carried by the 30 shaft.

The present invention is directed mainly 35 to the construction of an operating mechanism for the auxiliary bases and the means for lifting and propelling the main base and the machine supported thereon. One desired improvement brought about by the present 40 construction, is the character of step taken by the machine when propelled over the ground. The preferred performance is to first vertically lift the main base and machine thereon and then cause the machine to 45 travel horizontally while at the same time gradually moving downwardly so that the final settling motion of the machine at the end of the step is performed without jar or extensive vibration as would be the case 50 if such a heavy machine as an excavator, with its overhanging boom, were allowed to suddenly move downward two or three feet under its own weight. It is necessary to effect a considerable lift of the machine at 55 the beginning of a step in order to lift it

out of a depression which it may be in due to its own weight, and also to clear obstructions over which it must pass in its general horizontal motion. Another result accomplished by the use of the present construction, is to improve the walking action of the machine when making an ascent or descent over inclined ground, and also to prevent slippage of the machine at such times provided the inclination is not greater than the 60 safe limits for any such mechanism. The improved construction is also suitable for walking across ground inclined laterally of the direction of travel, in that the auxiliary bases are swiveled in such manner that they 65 may assume any reasonable angle in any direction with respect to the setting of the main supporting base of the machine.

The improved traction means is illustrated 70 in the accompanying drawings, in which:

Fig. 1 is a side view of a drag-line excavator provided with the traction means.

Figs. 2 and 3 are diagrams showing the 75 traction mechanism in moved positions over what is shown in Fig. 1.

Fig. 4 is a plan view of the main and auxiliary bases of the machine, but with the excavating machine proper, which rests upon the turntable of the main base, being 80 omitted.

Fig. 5 is an end view of the machine.

Fig. 6 is a side view of one of the auxiliary bases; and

Figs. 7 and 8 are sectional views respectively taken on the lines 7-7 and 8-8 of 90 Fig. 6.

The traction mechanism to which this invention relates is, to an extent, independent of the type of machine in connection with which it may be used, but the machine shown 95 in the drawings is what is known as a drag-line excavator having the customary main supporting base preferably circular in plan, and upon which is rotatably supported, through bearing rollers and a circular track, 100 the machine platform. This supports an engine having connections for operating the boom and drag-line, and for swinging the machine around the supporting base, and also having suitable reduction gearing and a clutch for transmitting motion from the engine to a horizontal shaft which extends outwardly from each side of the machine 105 and carries, through eccentrics, the auxiliary bases. Therefore, when the machine is 110

swung around the annular bearing on the main supporting platform, the auxiliary platforms are carried around with it and thus may be set for causing the machine to travel in any desired horizontal direction. The eccentrics on the horizontal shaft fit within horizontally extended openings in frames extending upwardly from the auxiliary platforms. The result of this construction is that when the horizontal shaft is rotated, the eccentrics first bear downwardly upon the frames of the auxiliary bases, lifting the main base and shifting it over the ground as the eccentrics roll along the extended openings in the frames of the auxiliary bases. As the eccentrics come to the end of these openings, the main base is lowered to the ground and further rotation of the eccentrics serves to lift the auxiliary bases and shift them in turn over the ground before allowing the auxiliary bases to come to rest, and again repeat the operation. A cam action occurs between the eccentrics and the frames of the auxiliary bases at the time the eccentrics are lifting and lowering the main base, otherwise pitman connections compel a positive action, while the eccentrics either roll in the openings in the frames of the auxiliary bases, or by rolling contact with the upper sides of the openings in the frames serve to shift the auxiliary bases. Pitmans or links are provided between the eccentrics and the frames of the auxiliary bases in order to positively compel the desired traveling motion while permitting slippage of the eccentrics when lifting.

The above described construction as shown in the drawings consists principally in the main base 1, auxiliary bases 2 and 3, the supporting platform 5 for the excavating machine, not completely illustrated but mainly contained with the housing 6, and including suitable operating means for the bucket supporting beam 7 and for the dragline 8 of the bucket 9. The machine platform 5 is provided with bearings for supporting a horizontal shaft 10, which is squared at its outer ends to rigidly carry eccentrics 11.

The new construction of auxiliary bases, and operating mechanism therefor is most clearly shown in Figs. 6 to 8. Each auxiliary base comprises a ground-engaging part 12 and an upwardly extending frame 13. This frame is provided with trunnions 14, fitting within bearings 15, and engages thrust blocks 16 on the part 12 of the base. This part of the base may therefore assume different angles according to the slope of the ground outwardly from the sides of the machine as illustrated in Fig. 5. The auxiliary bases may also conform to the slope of the ground in the direction of travel of the machine due to being free to rock around the eccentrics 11. The eccentrics 11 have

radially extending annular flanges 17 and 18 extending over the sides of frames 13 to prevent displacement of the frames with respect to the eccentrics. The frames 13 are shown as formed of two parts 19 and 20 connected together by bolts 21, and this permits fitting the frames over the eccentrics. Due to the considerable load which must be transmitted through the frames 13 to the auxiliary platforms 12, the latter are provided with concave bearing members 22 engaging the convex lower part 23 of frame 13. The trunnions 14 therefore do not have to transmit the entire load and may serve mainly to prevent displacement between the parts 12 and 13 of the auxiliary bases.

Each eccentric 11 is connected by a connecting rod or link 24 with the corresponding frame 13. These connecting rods serve to compel the desired motion between the eccentrics and the frames 13. For the purpose of supporting the connecting rods, the eccentrics are provided with studs 25 and the frames 13 are provided with studs 26.

The elongated openings 28 in the frame members 13 and within which the eccentrics 11 rotate are preferably sloped downwardly toward the direction of travel, in order to regulate the step accordingly and that when the machine is going up an incline, it may, after first being lifted by the eccentrics, travel forwardly in a substantially horizontal direction as the eccentrics roll along the lower trackways 29 of the openings 28.

In order to alternately lift the machine and lower it and likewise alternately lower the auxiliary bases and lift the same, it is necessary for the eccentrics to slip within the openings 18 when at the ends thereof. Hence these eccentrics and the openings are made with smooth surfaces. It is preferred not to employ teeth, but still to provide a positive drive as the eccentrics roll along the lower trackways 29 of the openings. The positive drive is provided for by the links 24. These links are free to oscillate around their pivots 26 as the opposite supporting pins 25 move in a circular path around the shaft 10, and have elongated apertures 31 at one of the pivots to compensate for the arc of oscillation.

The shaft 10 is supported in suitable bearings 30, and receives motion from the power unit 32 through clutch 33 and transmission 34.

In operation of the device, a driving connection is first made between shaft 10 and the power unit on the platform 5. Rotation of the shaft 10 is in the direction indicated by arrow 27 (Fig. 6). Thus the eccentrics, when turned in this direction and from the starting position indicated in Fig. 6, first bear downwardly on the lower trackways 28 of the parts 20 of the frames 13, slipping in these trackways while the shaft 10 is bodily

5 moved in an arc from the full line position in Fig. 6 to the dotted line position 10', then the eccentrics roll along the way 28 causing the machine to be pulled over the ground in a more or less horizontal direction, but preferably gradually toward the ground, due to the inclination of the way 28, so that the machine will finally come to rest gradually and without abruptly falling downward. In 10 this manner the stepping motion is made easy on the machine and less power is consumed in dragging the machine over the ground than if the motion were strictly horizontal from the lifting to lowering positions.

15 The connecting rods 24 always insure the correct position of the auxiliary bases with respect to the eccentrics. Nothing like what is known in this art as a misstep is possible. The auxiliary platforms are retained against 20 lateral displacement by the flanges on the eccentrics and the trunnions connecting the two parts of the auxiliary bases. These connections allow the necessary freedom of motion without binding in the mechanism.

25 Although but one specific embodiment of this invention has been herein shown and described, it will be understood that numerous details of the construction shown may be altered or omitted without departing 30 from the spirit of this invention as defined by the following claims.

I claim:

1. A mechanism of the class described, comprising a main supporting base, auxiliary bases located at the sides of said main supporting base, a horizontal shaft extending across said main supporting base and provided with toothless eccentric wheels at its ends engaging suitable coacting ways on 40 said auxiliary bases, means for driving said shaft, said ways being in the form of elliptical openings with their major axes extending in the horizontal direction transversely of said shaft, and having minor axes substantially the same as the diameter of the said 45 wheels.

2. A mechanism of the class described, comprising a main supporting base, auxiliary bases located at the sides of said main supporting base, a horizontal shaft extending across said main supporting base and provided with toothless eccentric wheels at its ends engaging suitable coacting ways on 50 said auxiliary bases, means for driving said shaft, and said ways being in the form of elongated or elliptical openings with their major axes extending in the horizontal direction transversely of said shaft, said ways being sloped from one end to the other.

60 3. A mechanism of the class described, comprising a main supporting base, auxiliary bases located at the sides of said main supporting base, a horizontal shaft extending across said main supporting base and 65 provided with toothless eccentrics at its ends

engaging suitable coacting ways on said auxiliary bases, connecting rods between said eccentrics and auxiliary bases, means for driving said shaft, and said ways being in the form of elongated or elliptical openings 70 with their major axes extending in the horizontal direction transversely of said shaft.

4. A mechanism of the class described, comprising a main supporting base, auxiliary bases located at the sides of said main 75 supporting base, a horizontal shaft extending across said main supporting base and provided with toothless eccentrics at its ends engaging suitable coacting ways on said auxiliary bases, connecting rods between said 80 eccentrics and auxiliary bases and arranged to allow for lost motion according to their arc of oscillation, means for driving said shaft, and said ways being in the form of elongated or elliptical openings with their 85 major axes extending in a horizontal direction transversely of said shaft.

5. A mechanism of the class described comprising a main supporting base, an auxiliary 90 base, a horizontal shaft mounted for rotation on said main supporting base, an eccentric carried by said horizontal shaft, said auxiliary base being provided with a horizontally extended way within which said eccentric rotates, and a pitman connecting 95 said eccentric with said auxiliary base.

6. A mechanism of the class described comprising a main supporting base, an auxiliary base, a horizontal shaft mounted for rotation on said main supporting base, an eccentric carried by said horizontal shaft, said auxiliary base being provided with a horizontally extended way within which said eccentric rotates, and a pitman connecting 100 said eccentric with said auxiliary base, said auxiliary base being formed of two parts 105 which are connected for relative oscillation around a horizontal axis.

7. A mechanism of the class described comprising a machine provided with a horizontally extending shaft and means for driving said shaft, an eccentric secured to said shaft, a traction means cooperating with said eccentric, said traction means having a horizontally extending opening within which said eccentric rotates, and a pitman connecting 110 said traction means with said eccentric.

8. A mechanism of the class described comprising a machine provided with a horizontally extending shaft and means for driving said shaft, an eccentric secured to said shaft, a traction means cooperating with said eccentric, said traction means having a horizontally extending opening within which said 120 eccentric rotates, and a pitman connecting said traction means with said eccentric, said opening being inclined in the direction of its 125 length with respect to the base line of said traction means.

9. A mechanism of the class described comprising a machine provided with a horizontally extending shaft and means for driving said shaft, an eccentric secured to said shaft, 5 a traction means cooperating with said eccentric, said traction means having a horizontally extending opening within which said eccentric rotates, and a pitman connecting said traction means with said eccentric, 10 said traction means having a base swiveled thereto on an axis extending in the direction of length of said opening.
10. A mechanism of the class described comprising a main supporting base, an auxiliary base for traction purposes having a frame structure provided with an elliptical opening, a horizontal shaft mounted for rotation in bearings upon said main supporting base, means on said supporting base for driving said shaft, an eccentric disk carried by said shaft and fitting within said elliptical opening in the frame of the auxiliary base, said auxiliary base and the frame thereof being swiveled together on an axis 25 extending in the direction of length of said opening.
11. A mechanism for transporting loads by step motions comprising a main supporting base and an auxiliary base, said main supporting base being provided with a horizontal shaft and means for driving said shaft, said auxiliary base being provided with a vertical frame having therein a way elongated in a horizontal direction and rounded at its ends on an arc the diameter of which is the same as the minor axis of 30 said way, a wheel fitting within said way, the diameter of which is the same as said minor axis, said wheel being eccentrically secured to said horizontal shaft.
12. A mechanism for transporting loads by step motions comprising a main supporting base and an auxiliary base, said main supporting base being provided with a horizontal shaft at one side of the center of gravity of the main supporting base, means on said main supporting base for driving said shaft, said auxiliary base being provided with a vertical frame having therein a way elongated in a horizontal direction and 35 rounded at its ends on an arc the diameter of which is the same as the minor axis of said way, a wheel fitting within said way the diameter of which is the same as said minor axis, said wheel being eccentrically secured to said horizontal shaft.
13. A mechanism for transporting loads by step motions comprising a main supporting base and an auxiliary base, said main supporting base being provided with a horizontal shaft and means for driving said shaft, said auxiliary base being provided with a vertical frame and having therein a way elongated in a horizontal direction 40 and rounded at its ends on an arc the diameter of which is the same as the minor axis of said way, a wheel fitting within said way, the diameter of which is the same as said minor axis, said wheel being eccentrically secured to said horizontal shaft.
14. A mechanism for transporting loads by step motions comprising a main supporting base and an auxiliary base, said main supporting base being provided with a horizontal shaft and means for driving said shaft, said auxiliary base being provided with a vertical frame and having therein a way elongated in a horizontal direction and 45 rounded at its ends on an arc the diameter of which is the same as the minor axis of said way, a wheel fitting within said way the diameter of which is the same as said minor axis, said wheel being eccentrically secured to said horizontal shaft.
15. A mechanism for transporting loads by step motions comprising a main supporting base and an auxiliary base, said main supporting base being provided with a horizontal shaft and means for driving said shaft, said auxiliary base being provided with a vertical frame and having therein a way elongated in a horizontal direction and 50 rounded at its ends on an arc the diameter of which is the same as the minor axis of said way, a wheel fitting within said way the diameter of which is the same as said minor axis, said wheel being eccentrically secured to said horizontal shaft.
16. A mechanism for transporting loads by step motions comprising a main supporting base and an auxiliary base, said main supporting base being provided with a horizontal shaft and means for driving said shaft, said auxiliary base being provided with a vertical frame and having therein a way elongated in a horizontal direction and 55 rounded at its ends on an arc the diameter of which is the same as the minor axis of said way, a wheel fitting within said way the diameter of which is the same as said minor axis, said wheel being eccentrically secured to said horizontal shaft.
17. A mechanism for transporting loads by step motions comprising a main supporting base and an auxiliary base, said main supporting base being provided with a horizontal shaft and means for driving said shaft, said auxiliary base being provided with a vertical frame and having therein a way elongated in a horizontal direction and 60 rounded at its ends on an arc the diameter of which is the same as the minor axis of said way, a wheel fitting within said way the diameter of which is the same as said minor axis, said wheel being eccentrically secured to said horizontal shaft.
18. A mechanism for transporting loads by step motions comprising a main supporting base and an auxiliary base, said main supporting base being provided with a horizontal shaft and means for driving said shaft, said auxiliary base being provided with a vertical frame and having therein a way elongated in a horizontal direction and 65 rounded at its ends on an arc the diameter of which is the same as the minor axis of said way, a wheel fitting within said way the diameter of which is the same as said minor axis, said wheel being eccentrically secured to said horizontal shaft, and a connection between said wheel and auxiliary base for positively shifting the auxiliary base.

Signed at Chicago this 21st day of April
1925.

OSCAR J. MARTINSON.
